ELECTRODE HOLDER

Roy M. Stafford, Beaumont, Tex.

Application June 4, 1942, Serial No. 445,699

10 Claims.

(Cl. 219—8)

This invention relates to electric arc welding and more particularly to improvements in weld rod or electrode holders for use in such method of welding.

An object of the invention is to provide a holder which is simple in construction and operation and which is capable of extensive and efficient use without repair.

Another object is to provide a holder in which the electrode is gripped by relative rotation of parts, one of which is provided with a floating or swivel contact to move into desired engagement with the weld rod or electrode and at the same time to have a wiping and efficient engagement with the conductive body of the holder.

Still another object is to provide a holder including a conductive body with a floating contact on one end thereof, such contact being provided with an axial stem extending into and swivelly connected to the body.

A further object is to provide a grooved stem on the floating contact to receive metal displaced therein and swivelly hold the contact in place upon the holder body.

A still further object is to provide a holder comprising a body with a floating contact on one end thereof, the body and contact having complementary annular end faces which move into frictional engagement and provide a low resistance connection between the body and contact when an electrode is clamped against the outer end of such contact and the holder is ready for use.

The foregoing objects together with additional objects will be more fully apparent from the following description taken in connection with the accompanying drawing in which:

Fig. 1 is a longitudinal sectional view of an illustrative embodiment of the invention;

Fig. 2 is a sectional view taken on the line 2—2 in Fig. 1;

Fig. 3 is an enlarged sectional view of a modified form of the floating contact feature shown in Fig. 1;

Fig. 4 is another enlarged sectional view of the floating contact feature showing the use of displaced metal from the body of the holder for holding the floating contact in place.

In the illustrated embodiment of the invention shown in the drawing the body member 1 of conductive material is provided with a radial flange 2 and threaded areas 3 and 4 at opposite sides thereof. The handle 5 of insulated material has a bore 6 to receive the flange 2. The bore 6 has a reduced portion which is internally threaded for engagement with the threaded area

3 and which also provides a shoulder 7 which is engaged by the flange 2 on the body 1. Beyond the threaded area 3 the bore in the handle 5 is enlarged sufficiently to receive a conductor cable 10 comprising conductors 11 and insulation 12 covering such conductors. The conductors 11 are secured to the body 1 in any suitable manner such as soldering, brazing, or suitable mechanical clamping means such as that shown in my copending application Serial No. 389,167, filed April 18, 1941.

An important feature of the invention resides in the manner of obtaining the desired conductive engagement between the body 1 and the electrode 15 held by the holder. This feature, to which reference will now be made, is such that the desired engagement is effected with each and every electrode consumed through the use of the holder over a long period of time.

20 The electrode holder and the electrode held thereby should constitute a relatively rigid assembly so that the operator is assured at any instant of the angular direction of extension of the electrode 15 radially of the handle 5. At the same time it is, of course, imperative that an efficient conductive path for the flow of electric current from the body 1 to the electrode 15 be provided. This means that considerable clamping pressure with the electrode be had. Such clamping pressure tends to form a slight transverse indentation in the end of the member making engagement with the periphery of the electrode. Once such indentation is initiated, repeated clamping has a cumulative effect. Such cumulative effect is accompanied by a tendency of the indentation to also be enlarged angularly of the surface making engagement with the electrode. This condition creates a tendency for an inefficient contact to be formed and also a tendency to produce unthreading of the holder whereby conductive contact becomes inferior and the rigidity of the holder-electrode assembly is destroyed.

45 My construction avoids the difficulties just enumerated by providing a floating or swivel contact to effect a conductive connection between the holder body and the electrode gripped by the holder. In Fig. 1 of the drawing the body 1 is shown as having a counterbore 13 which provides a radial shoulder 14 proximate the outer end of the body. The floating contact is shown at 16 and comprises a head portion 17 and a stem portion 18 of which the latter extends inwardly and slightly beyond the shoulder 14. The inner end of the stem portion 18 is upset in any

suitable manner so that the contact 16 is swivelly held in place upon the outer end of the body member 1. It seems obvious that the end of the body member and the annular axially facing surface on the head 17 are complementary and engage to form a conductive connection between the head 17 and the body 1.

Surrounding the outer end of the body member 1 and the contact 16 is a cap member 20 which has a roughened peripheral surface 21 to provide desired adherence with insulation 22 formed thereabout. The cap member is threaded internally for engagement with the threaded portion 4 on the body 1. Adjacent its outer end the cap member 20 is provided with a transverse opening 23 to receive the electrode 15.

The operation of the holder as thus far described is believed apparent. By way of summary it will be pointed out that an electrode 15 to be used by the holder is inserted in the opening 23 whereupon the cap member 20 is rotated to move such member axially of the body member 1 whereby the electrode engages the end surface of the floating contact 16. Continued relative rotation between the cap member 20 and the body 1 effects a clamping action between the floating contact and the electrode. At the same time, however, and during the tightening process, the head 17 will rotate to some extent relative to the body 1 and will thus produce a wiping action whereby a desired electrical contact is provided between the floating contact and the body. This feature is of importance inasmuch as a certain amount of oxidation occurs because of the elevated temperature which exists from the normal use of the holder.

In Fig. 3 the floating contact 16' differs from that shown in Fig. 1 in that the outer surface is tapered at 25 and the opening 23' transversely of the cap member 20' meets the axis thereof at the same angle as the bevel surface 25'. As indicated in my copending application to which reference is above made, this feature provides an increased contacting surface, increased leverage in the application of pressure to the electrode, and holds the electrode at an angle to the body of the holder, a position which is desirable with some operators and in effecting welds in areas otherwise relatively inaccessible.

In Fig. 4 the body 1 is shown as solid except for a bore 26 in the end thereof to receive the stem 18' of the floating contact 16''. In this embodiment the stem 18' is provided with an annular groove 27 into which a portion of the wall surrounding the bore 26 is displaced inwardly as shown at 28, whereby the floating contact is desirably held in place upon the end of the body 1.

Broadly, the invention comprehends improvements in electrode holders whereby there is provided a floating contact connection between the holder body and the electrode so that the electrode is firmly and conductively attached to the body at all times.

What is claimed is:

1. An electrode holder comprising a generally cylindrical conducting member having one end thereof adapted for conductive attachment to a conductor cable, a handle of insulating material attached to said member and extending outwardly over said end, the electrode end of said member extending outwardly from the handle and having a threaded area thereon, a contact swivelly mounted on said member, an annular transverse contact face thereon engageable with a wiping contact and a weldrod, and a cap member threaded internally for engagement with said threaded area, there being a transverse opening through said member to receive an electrode and effect interengagement of the electrode and contact face, to insure a circuit with the conductive member by relative rotation between the conductive and cap members.
2. In an electrode holder the combination of, a conductive body member and a surrounding cap member movable axially of each other upon relative rotation thereof, a contact member swivelly mounted upon the end of the body member within the cap member, there being a transverse opening in the cap member to receive an electrode and effect a conductive connection from the body through the contact member to the electrode when the body and cap member are moved axially toward each other, said contact member having a flat end contact face to bear against the electrode across its width so as to clamp the electrode against the cap.
3. In an electrode holder the combination of, a conductive body member having a peripheral threaded area thereon, an opening in the outer end thereof, a contact member swivelly mounted in said opening and having an annular surface thereon complementary and engageable with the end of the body about the opening, and a cap member surrounding the end of the body and engaging said threaded area, there being a transverse opening through said cap member to receive an electrode and effect a conductive connection from the body through the contact member to the electrode upon relative rotation of the body and cap members.
4. In an electrode holder, a conductive body member having an axial bore, a contact member swivelly mounted upon the end of said body member, said contact member including a head portion engageable with the end of the body member and a stem portion extending into said bore, and a cap member surrounding the end of said body member and said contact member and movable axially thereof upon relative rotation of the cap and body members.
5. In an electrode holder, a conductive body member having an axial bore, a contact member mounted thereon, said contact member including a head portion overlying the end of the body member and a stem integral with said head portion extending into said bore, a peripheral groove in said stem portion, body material displaced inwardly into said groove whereby the contact member is swivelly mounted upon the body member, and means rotatably and axially movable on said body to move an electrode into engagement with the end surface of the contact member.
6. In an electrode holder, a conductive body member having an axial bore, a shoulder in said bore, a contact member mounted on the end of the body member, said contact member including a head portion overlying the end of the body member and an integral stem extending into said bore, means on said stem engageable with the shoulder to swivelly hold the contact member in position on the end of the body, and means rotatably mounted on the body and movable axially thereof to move an electrode into engagement with the end surface of the contact member.
7. In an electrode holder a contact member to make the electrical connection with the electrode, means to swivelly mount said member, and means to force the rod against said member with a rotative action so as to improve the electrical contact, said member having a cylindrical head with

a circular flat end face to provide a line contact across its diameter so as to hold the electrode against tilting movement.

8. An electrode holder for welding comprising a handle, a conductive member, a cap telescoped over said member and threaded to move axially upon relative rotation, a pair of opposite electrode openings in the cap, a contact head rotatably mounted at the end of said conductive member, a flat end face on said head to bear against the side of the electrode passed thru said openings whereby the electrode is clamped rigidly by screwing said cap on to said member and held against tilting by the flat face forcing the electrode against the side of the openings.

9. An electrode holder for welding comprising a handle, a conductive member, a cap telescoped over said member and threaded to move axially upon relative rotation, a pair of opposite electrode openings in the cap, a contact head rotatably mounted at the end of said conductive member, a flat end face on said head to bear against

the side of the electrode passed thru said openings whereby the electrode is clamped rigidly by screwing said cap on to said member and held against tilting by the flat face forcing the electrode against the side of the openings, said member and contact head having seating shoulders to transmit the thrust of the clamping action.

- 5 10 15 20
10. An electrode holder for welding comprising a handle, a conductive member, a cap telescoped over said member and threaded to move axially upon relative rotation, a pair of opposite electrode openings in the cap, a contact head rotatably mounted at the end of said conductive member, a flat end face on said head to bear against the side of the electrode passed thru said openings whereby the electrode is clamped rigidly by screwing said cap on to said member and held against tilting by the flat face forcing the electrode against the side of the openings, said cap having an insulating covering thereon.
